United States Patent Office.

GEORGE L. WITSIL, OF PHILADELPHIA, PENNSYLVANIA.

Design No. 3,007, dated April 21, 1868.

DESIGN FOR A TRADE-MARK.

The Schedule referred to in these Letters Patent and making part of the same.

TO ALL WHOM IT MAY CONCERN:

Be it known that I, GEORGE L. WITSIL, of Philadelphia, in the county of Philadelphia, and State of Pennsylvania, have invented a new Design for a Trade-Mark; and I do hereby declare that the following is a full, clear, and exact description of the same, reference being had to the annexed drawings and specimen, making a part of this specification, in which the said design is shown.

Said design consists in the words "The Dexter" printed upon a scroll, the letters having stars between them, and a United States flag placed between the words. Below these words is the figure of a horse, and below this figure the words "Washing-Machine," the letters being in like manner separated by stars, and the words by a similar but larger flag. Under these words are the following words: "Patented November 5, 1867."

What I claim as my invention, and desire to secure by Letters Patent, is—

A design for a trade-mark, substantially as set forth and shown.

In testimony whereof, I have signed my name to this specification in the presence of two subscribing witnesses.

GEO. L. WITSIL.
